CLAIM

The ornamental design for a luggage case, as shown and described.

DESCRIPTION

FIG. 1 is a front, top, right-side perspective view of a luggage case according to the present disclosure;

FIG. 2 is a rear, bottom, left-side perspective view thereof;

FIG. 3 is a front elevational view thereof;

FIG. 4 is a rear elevational view thereof;

FIG. 5 is a left-side elevational thereof;

FIG. 6 is a right-side elevational thereof;

FIG. 7 is a top plan view thereof; and,

FIG. 8 is a bottom plan view thereof.

Any shading lines are not features of the design but are utilized to illustrate the surface contours of the luggage case in the drawings.

1 Claim, 8 Drawing Sheets(56)
